UNITED STATES PATENT OFFICE.

HENRY NOEL POTTER, OF HALENSEE, GERMANY, ASSIGNOR TO GEORGE WESTINGHOUSE, OF PITTSBURG, PENNSYLVANIA.

SYSTEM OF ELECTRIC LIGHTING ON CONSTANT-CURRENT CIRCUITS.

SPECIFICATION forming part of Letters Patent No. 680,809, dated August 20, 1901.

Application filed October 3, 1900. Serial No. 31,831. (No model.)

To all whom it may concern:

Be it known that I, HENRY NOEL POTTER, a citizen of the United States of America, and a resident of Halensee, Germany, have 5 invented certain new and useful Improvements in Systems of Electric Lighting on Constant-Current Circuits, of which the following is a specification.

My invention relates to an arrangement of 10 circuits and apparatus for the operation upon constant-current circuits of lamps having a plurality of glowers made of a material which requires to be heated in order to become conductive, the object being to provide automatic means for cutting out any lamp when 15 it is out of order and also means for indicating at all times the condition of any given lamp.

In practice I employ a cut-out for the 20 entire lamp in addition to the usual heater cut-out, and I usually employ an incandescent pilot-lamp in a shunt to each multiglower-lamp controlled by a rise of voltage in the 25 circuit. I also provide ballast resistances in series with the several glowers; but these resistances are usually not corrective ballasts, but are merely German-silver wires of a few ohms resistance, the resistances being so chosen as to cause the current to divide up 30 properly among the glowers constituting the luminous elements of the lamp.

My invention will be understood by reference to the accompanying drawing, which is a diagram of an electric circuit containing 35 multiple glower-lamps in series, one of the lamps being shown in diagram in connection with the extra cut-out and the indicating devices for showing when the lamp is out of order.

40 In the drawing, 1 is any suitable generator of electricity, and 2 and 3 are mains leading therefrom. Multiglower-lamps of the character described are shown at 4, 5, and 6, the last-named lamp being illustrated diagrammatically with considerable detail.

45 Referring to the apparatus connected with the lamp 6, 7 and 8 are glowers of the character described and 8 8 are ballast resistances, generally of German silver, one in series with 50 each glower. The object of these resistances

is to make the current split up properly among the several glowers of the lamp. At 9 is shown an electric heater of any suitable type intended to bring the glowers to a conductive state in the usual manner.

55 In going to the lamp 6 the main 3 passes to the contact-point 10 of an electric cut-out and through the movable part 11 of the said cut-out to the second stationary cut-out point 12 thereof. From the point 12 the main circuit 60 proceeds in a similar way through the heater cut-out for the lamp, the stationary point of this cut-out being shown at 13 and 15 and the movable part thereof being shown at 14. Branches from the main wire 3 pass 65 through the actuating-coil 16 of the heater cut-out and also through the actuating-coil 17 of a second cut-out, the object of which will be described farther on. The action of 70 the heater cut-out is similar to that of the usual electromagnetic cut-out in lamps of this class. When the glowers of the lamp 6 have become heated until they are themselves sufficiently good conductors of the electric current, a considerable portion of the current 75 on the line is shunted through the glowers and through the coil 16, which coil then lifts the movable contact 14 from the cut-out points 13 and 15, thus rupturing the heater-circuit. The coil 17 is an actuating-coil for 80 a cut-out whose contacts are in series with the whole current to the heater and glowers. This actuating-coil 17 is in series with a resistance 19 and a resistance 20, the latter being connected through a switch 21 to the 85 main 2. The resistance 20 may well be an incandescent lamp so designed as to take the full current ordinarily taken by the lamp 6, though not necessarily designed for the full voltage of the latter. The lamp 20 may be 90 replaced by the actuating-coil 22 of a semaphore 23. I have indicated this construction in dotted lines in the drawing. On the shaft of the semaphore 23 I show a toothed segment 24, which engages with a rack 25 on the core 95 of the coil 22. The action is obvious.

95 In operation the lamp first takes current through the heater, and a slight excess current passes through the coil 17, the resistance 19, and the incandescent lamp 20. This ex- 100

cess current is insufficient, however, to raise the armature of the cut-out coil 17. When a sufficient number of the glowers have become conductive, the cut-out coil 16 does its work 5 in the manner already described, thus cutting the heater out of the circuit. Inasmuch as we are here operating upon a constant current it is desirable that the cut-out apparatus for the heater-circuit should be as sensitive as possible. Should one of the glowers break, the total current will then flow through the remaining five glowers, causing the voltage to rise, but not endangering the ballasts, as would be the case if the latter were of the 15 usual corrective type. When the voltage has risen sufficiently to cause an excess current to flow through the coil 17, (which excess current will be further aided by the decreasing resistance of the incandescent lamp 20,) the 20 core of the cut-out coil 17 is drawn up, interrupting the current to the lamp.

Above the movable element 11, which usually bridges the contacts 10 and 12, are two other stationary contacts 26 and 27, arranged 25 in a shunt around the resistance 19. When the circuit of the lamp has been interrupted, as above described, thus throwing the entire current through the coil 17, the resistance 19, and the lamp 20, the movable element 11 is 30 drawn violently up against the contacts 26 and 27, in which position the resistance 19 is cut out. The current formerly passing through the lamp now traverses the coil 17 and the incandescent pilot-lamp 20, indicating 35 that the lamp 6 is out of order. By opening the switch 21 and closing a switch 28 in the circuit of the semaphore-operating coil 22 the semaphore itself will be set to indicate an abnormal condition in the lamp 6. This 40 is in fact the condition of the circuit indicated in the drawing. In general it is not my purpose to provide the alternative construction indicated in the drawing, but to select either an incandescent lamp or a semaphore-coil and connect the one or the other 45 permanently with the lamp apparatus. The semaphore would have the advantage over the incandescent lamp of continuing to indicate the abnormal condition after the entire 50 circuit should for any reason have been opened. All the advantages of both devices may be secured by connecting up an incandescent lamp and the semaphore device in series or in parallel as a substitute for either 55 device alone. In some instances I prefer to use the duplicate devices last mentioned. Manifestly the described apparatus indicates 60 the actual condition of the lamp with which it is connected, whether such condition is normal or abnormal, the luminous or non-luminous condition of the incandescent lamp

or the position of the semaphore-arm being a sufficient indication for this purpose.

The invention claimed is—

1. The combination with a multiglower- 65 lamp of the class described, of a pilot-lamp in a normally closed shunt thereto, adapted to become luminous when the multiglower-lamp is out of order.

2. The combination with a multiglower- 70 lamp of the class described, of a cut-out for the lamp operated by a rise of voltage in the lamp-circuit, such cut-out operating to break the lamp-circuit when one of the glowers breaks or becomes inoperative for any reason. 75

3. The combination with a multiglower-lamp of the class described, of a cut-out for the heater of said lamp, and a second cut-out for the entire lamp, the said second cut-out being operated by a rise of voltage in the 80 lamp-circuit.

4. The combination with a multiglower-lamp of the class described, of a high-resistance shunt to the said lamp, and means for breaking the lamp-circuit and throwing the 85 entire current through the shunt when one of the glowers of the lamp breaks or becomes inoperative, for any reason.

5. The combination with a multiglower-lamp of the class described, of a high-resistance 90 shunt containing an incandescent pilot-lamp, and means for breaking the circuit of the multiglower-lamp and passing the current through the pilot-lamp when one or more of the glowers become inoperative. 95

6. The combination with a multiglower-lamp of the class described, of a shunt-circuit thereto containing a resistance and an indicating device, means for breaking the 100 circuit of the lamp when one of the glowers becomes inoperative, and means for cutting out the resistance when the cut-out for the lamp is operated.

7. The combination with a multiglower-lamp of the class described, of a variable-resistance shunt including an indicating device, the said shunt containing a cut-out which is operated by a rise of voltage in the lamp-circuit. 105

8. In a system of electric lighting by multiglower-lamps of the class described on constant-current circuits, a series of such lamps, each having an automatic cut-out operated by a rise of voltage in the lamp-circuit, such cut-out acting to break the circuit of the lamp 115 when one of the glowers breaks or becomes inoperative for any reason. 110
